UNITED STATES PATENT OFFICE.

ALBERT C. MORK, OF MINNEAPOLIS, MINNESOTA.

VALVE-GRINDING MACHINE.

1,327,875.

Specification of Letters Patent. Patented Jan. 13, 1920.

Application filed July 12, 1919. Serial No. 310,408.

To all whom it may concern:

Be it known that I, ALBERT C. MORK, a citizen of the United States, residing at Minneapolis, in the county of Hennepin and State of Minnesota, have invented certain new and useful Improvements in Valve-Grinding Machines; and I do hereby declare the following to be a full, clear, and exact description of the invention, such as will enable others skilled in the art to which it appertains to make and use the same.

My invention has for its object to provide an improved machine for the grinding of valves of multi-cylinder engines such as used in automobiles and other motor propelled vehicles.

Generally stated, the invention consists of the novel devices and combinations of devices hereinafter described and defined in the claims.

This improved valve grinding machine is adapted to be quickly applied to a multi-cylinder engine and to be used to simultaneously grind a plurality of valves to-wit, all of the valves of an ordinary multi-cylinder engine. The machine involves simple and efficient means for oscillating these valves and for intermittently lifting and lowering the same and for progressively moving the valves so that the grinding operations will be shifted from place to place as the grinding action progresses.

The machine is illustrated in the accompanying drawings, wherein like characters indicate like parts throughout the several views.

Referring to the drawings:

Figure 1 is a plan view with some parts broken away showing the grinding machine applied to a multi-cylinder engine;

Fig. 2 is a fragmentary section taken on the line 2—2 of Fig. 1;

Fig. 3 is a front elevation showing the right hand portion of the machine, some parts being broken away; and

Fig. 4 is a vertical section taken on the line 4—4 of Fig. 1, some parts being broken away.

In Fig. 1 the engine cylinder casting is indicated as an entirety by the numeral 5. This cylinder casting has a multiplicity of alined cylinders 6 and threaded bolt holes 7, such being the usual construction.

For positively securing the valve grinding machine to the cylinder casting, I use preferably two angle brackets 8, the base por-

tions of which are adapted to rub on the top of the cylinder casting and are provided with slot 9 through which the machine screws 10 are adapted to be passed and screwed into the proper holes 7, to rigidly secure the said brackets as indicated.

The upper portions of the bracket 8 are rigidly secured to and support a horizontal guide bar 11 that is rectangular in cross section. Slidably mounted on the guide bar 11, is a plurality of bracket-like bearing heads 12. These bearing heads 12 have upper and lower flanges 12^a that slide on the top and bottom edges of the bar 11 and overlap the same at the bar. These screws 13 pass through the upper legs 12^a, impinge on the upper edge of the bar 11 to rigidly and adjustably hold said bearing head in properly spaced position.

Rotatively mounted in the probably projected upper arms of the bearing head 12, are upright tubular spindles 14. Grinder stems 15 are mounted for rotary and endwise movements in the lower forwardly projected portions of the several bearing heads 12, and extend axially through the respective tubular spindles 14 and have screw threaded engagements with the upper portions thereof. Nuts 16 on the threaded upper ends of the stems 15 secure the said stems and tubular spindles for common rotary movements and for common vertical reciprocatory movements. At their depending lower ends the stems 15 are shown as provided with pronged heads which, by means of screws 17, or the like, are attached to the upper ends of screw-driver like valve engaging stems 18. Spur gears 19 are screwed on the respective stems 15 and are located just above the bottoms of the coöperating bearing head 12. The key connections 19^a between the gears 19 and the said stems 15, permit the said stems to move vertically through the said gears, but cause said gears to rotate with the said stems.

To hold the gears 19 down, that is to prevent the same from rising with the stems, when the latter are raised, stop pins 20 are shown as passed through the side flanges of the head 12, just above the section gear 19.

These several gears or pinions 19 mesh with a common long rack bar 21 that is mounted to slide, in a groove formed in the front space of the guide bar 11, and through passages in the respective bracket 12. Mounted on each tubular spindle 14 is a sleeve 22 that is provided with forwardly

projected arms 22^a that are bifurcated and provided with rollers 23. Arms 22^a work between laterally spaced side plates of the respective bracket 12 and thereby hold the sleeves 22 against rotation with respective tubular spindle 14. The said sleeves 22, however, are caused to move vertically with the respective tubular spindle and coöperating stem 15. To cause this common vertical movement, the sleeves 22 are held between shoulders on the upper portion of the respective tubular spindle 14 and nut 24 applied to the extreme lower ends of said tubular spindle, (see particularly Fig. 4).

15 The roller 23 of the several sleeves 22 are operated upon by cams 25 that are keyed to rotate with, but to slide on common shaft 26. Shaft 26 is journaled in bearings 27 and 28 on the guide bar 11, and is extended 20 through laterally spaced guide plate portion 12^b of the several bearing heads. The connections between the shaft 26 and cams 25, permit the said cams to slide freely on said shaft, and such movements of the cams are 25 produced by the sliding movement of the respective bearing heads. Otherwise stated, the cams are always held in proper, coöperative relation to the respective bearing head and parts carried thereby.

30 The bearing 27 is preferably in the form of a yoke and is fixed to the right hand end of the guide bar 11, as shown in Fig. 1. To the right hand end of shaft 26 is secured a beveled gear 29 that meshes with a bevel 35 gear 30 secured on a short shaft 31 mounted in the bearing bracket 27. The inner end of shaft 31 is provided with crank arm 32 equipped at its end with a roller 33, but works in the vertically elongated slot of a 40 head 34 that is pivoted to the right hand end of the bar 21.

At its front end the slot 21 is provided with an operating handle or crank lever 35 by means of which it may be hand operated. 45 In a power driven machine, however, a pulley may be substituted for this hand crank 35. For an important purpose, the gears 29 and 30 are made of unequal diameter, preferably teeth differing in number and having 50 no common factor. When shaft 31 is rotated by crank 35, crank 32 will move rack bar 21 longitudinally along the supporting bar 11, and such movement of said rack will cause a gear 19 to make approximately complete rotation, first in the one direction and then in the other. Such rotary movements of the said figure will cause the stems 15 and 18 to make corresponding oscillation and when the end of stem 18 is engaged with the 55 valves, said valves will also, of course, be correspondingly oscillated. The valves, as is well known, are spring-pressed upward so that they rise from their seat when pressure is released therefrom. When the rollers 23^a 60 ride upon the concentric portions of the cam

25, springs 14^a, which are compressed between the upper arms of the respective head 12 and shoulders on the coöperating non-rotary sleeves 22, serve to overcome the springs of the several valves and force the 70 said valves against their seats so as to produce the grinding action. The valves will be held to their seats, and the grinding action produced throughout about three-fourths of each oscillatory rotation of said valve. During the other approximately one-fourth rotary oscillation, the cams 25, acting on the rollers 23^a, will raise the sleeves 22 and stems 15 and 18 and permit the valves, under the action of their springs, to be lifted from 80 their seats.

As cam shaft 26 is rotated at higher speed than cam 31 and crank arm 32, the point at which the cams will allow the valves to drop against their seats, will be continuously advanced and a grinding action continuously shifted. With the described beveled gear connection between shafts 21 and 26, there will be no repetition or, at least, no frequent repetition of grinding action throughout exactly the same zone. This machine will therefore, produce a better grinding action than can be produced by hand.

By sliding adjustments of the several heads on the supporting bar 11, the several 95 valve grinding devices may be properly spaced to come into position over the several valves of the engine. The valves of the engine are, as is well known, always located in direct line so that the above adjustments 100 of the grinding device is possible.

In actual practice the efficiency of this 105 valve grinding device has been demonstrated.

What I claim is:

1. A valve grinding machine comprising a supporting bar having means for attaching the same to a cylinder casting, supporting heads adjustable on said supporting bar, valve engaging grinder stems mounted in 110 said head for rotary and vertical movements, springs yieldingly forcing said grinder stems downward, gears rotatable with the said stems, a rack bar slidably mounted in respect to said supporting bar 115 and engaging the several gears, a cam shaft supported from said bar and extending along the several heads, cams rotatable with, but slidable on said cam shaft, and non-rotary cam engaged devices movable 120 vertically with the several grinder stems, said head having webs that embrace the respective cams and cause the same to move, therewith along said cam shaft.

2. A valve grinding machine comprising 125 a supporting bar having means for attaching the same to a cylinder casting, supporting heads adjustable on said supporting bar, valve engaging grinder stems mounted in said head for rotary and vertical move- 130

ments, springs yieldingly forcing said grinder stems downward, gears rotatable with the said stems, a rack bar slidably mounted in respect to said supporting bar and engaging the several pinions, a cam shaft supported from said bar and extending along the several heads, cams rotatable with but slideable on said cam shaft, non-rotary cam engaged devices movable vertically with the several grinder stems, a drive shaft having a crank operative to reciprocate rack bar, and gears connecting said latter shaft to said cam shaft for rotating the same.

15 3. A valve grinding machine comprising a supporting bar having means for attaching the same to a cylinder casting supporting heads adjustable on said supporting bar, valve engaging grinder stems mounted in 20 said head for rotary and vertical movements, springs yieldingly forcing said grinder stems downward, gears rotatable with the said stems, a rack bar slidably mounted in respect to said supporting bar 25 and engaging the several gears, a cam shaft supported from said bar and extending along the several heads, cams rotatable with, but slideable on said cam shaft, non-rotary cam engaged devices movable vertically with the several grinder stems, a shaft 30 having a crank operative to reciprocate rack bar, gears connecting said two shafts for rotating said cam shaft, the said gears being of equal diameter so that the cam action 35 will be shifted in respect to the rack movement.

4. In a valve grinding machine the combination with a supporting bar and means for securing the same to the cylinder casting of an engine, of a plurality of supporting heads slidably mounted on said supporting bar, a vertically movable grinding stem mounted in each bearing head, a gear fixed against vertical movements, but rotatable with each such grinder stem, a rack bar 45 slidably mounted on said supporting bar and meshing with said several gears, a cam shaft supported from said supporting bar and extended along the several bearing 50 heads, cams on said cam shaft slideable thereon, but rotatable therewith, a non-rotary sleeve surrounding each grinder stem and vertically movable therewith, said/

sleeves having arms subject to the respective cams, springs yieldingly pressing said sleeve and stems downward, a driving shaft mounted on a part carried by said supporting bar and having a crank at its inner end equipped with a crank pin engageable with a head on said rack to reciprocate the latter, 60 and bevel gears connecting said driving shaft to said cam shaft for rotating the latter, the said bearing heads having laterally spaced webs that hold said sleeves against rotation and cause the respective 65 cams to slide therewith.

5. In a valve grinding machine the combination with a supporting bar and means for securing the same to the cylinder casting of an engine of a plurality of supporting heads slidably mounted on said supporting bar, a vertically movable grinder stem mounted in each bearing head, a gear fixed against vertical movements, but rotatable with each such grinder stem, a rack 70 bar slidably mounted on said supporting bar and meshing with the several gears, a cam shaft supported from said supporting bar and extended along the several bearing heads, cams on said cam shaft slideable 75 thereon, but rotatable therewith, a non-rotary sleeve surrounding each grinder stem and vertically movable therewith, said sleeves having arms subject to the respective cams, springs yieldingly pressing said 80 sleeve and stems downward, a driving shaft mounted on a part carried by said supporting bar and having a crank at its inner ends equipped with a crank pin engageable with a head on said rack to reciprocate 85 the latter and bevel gears connecting said driving shaft to said cam shaft or rotating the latter, the said bearing heads having laterally spaced webs that hold said sleeves against rotation and cause the respective 90 cams to slide therewith on the said cam shaft, the said beveled gears being of unequal diameter and having different number of feet.

In testimony whereof I affix my signature 100
in presence of two witnesses.

ALBERT C. MORK.
